DESIGN FOR A COMBINED GRAVE MARKER AND URN

Joseph M. Majewski, Jr., Kansas City, Mo.

Application October 1, 1937, Serial No. 71,906

Term of patent 14 years

To all whom it may concern:

Be it known that I, Joseph M. Majewski, Jr., residing at Kansas City, in the county of Jackson and State of Missouri, have invented a new, original, and ornamental Design for a Combined Grave Marker and Urn, of which the following is a specification, reference being had to the accompanying drawing forming part thereof, in which grave marker and urn, showing my new design.

I claim:

The ornamental design for a combined grave marker and urn substantially as shown.
